DEVICE FOR COLOR PHOTOGRAPHY

**Karl Klopp, Arlington Heights, Ill., assignor to
Marie Klopp, Chicago, Ill.**

Refiled for abandoned application Serial No.
118,659, December 31, 1936. This application
January 4, 1938, Serial No. 183,363

5 Claims. (Cl. 95—2)

This application refers to my application Serial No. 118,659, filed December 31, 1936 (now abandoned), for which this application is being refiled.

5 This invention relates to the process of direct color photography and has for one of its objects to produce in standard or any other desired size, as often as needed, the different colors of variously colored objects by means of direct photography.

10 While formerly this was done in a "one" or in a "three in one camera," a plurality of colors of objects may be reproduced with this device.

Another object is to provide a frame into which 15 dry, wet, or emulsion plates of standard or other size may be fitted to permit perfect register of any number of exposed color plates.

Another object is to provide a frame having adjustable side members whereby to accommodate 20 various sizes of plates.

With these and other objects in view the invention will be better understood by referring to the following specification and accompanying drawings wherein like numerals represent corresponding parts and:

25 Fig. 1 is an elevational view of the device with a color plate clamped in position and partly broken away.

Fig. 2 is a section taken on the line 2—2 of 30 Fig. 1.

Fig. 3 is an enlarged detail view taken on the line 3—3 of Fig. 1.

Fig. 4 is a modified detail of the frame construction.

35 Fig. 5 is a section taken on the line 5—5 of Fig. 4.

Fig. 6 is a plan view of a register mark for offset or rotogravure printing positive.

Fig. 7 is a plan view of a register mark for 40 photoengraving or typaprinting.

Fig. 8 is a plan view of a register mark for offset or rotogravure printing negative.

Fig. 9 is an elevational view of a modified form of frame.

45 Fig. 10 is a top plan of a position of the top rail of Fig. 9.

Fig. 11 is an enlarged section taken on the line 11—11 of Fig. 9, and

50 Fig. 12 is a perspective view of one of the upper right members of Fig. 9.

Referring more particularly to Figs. 1 to 8 inclusive, 1 indicates a rectangular frame having a top wall 2, bottom wall 3 and side walls 4 and 5 respectively. Arranged on the outer periphery of the walls 2 to 5 inclusive in close proximity

to the front face 6 of the frame 1 is a rib 7 having sets of saw like teeth 9 arranged longitudinally thereon adjacent the corners 10 thereof. The teeth 9 are adapted to hold the frame 1 in immovable position in a camera during the loading and exposing of the sensitized material. Arranged on the inner face of the walls 3 and 4 in close proximity to their ends are wedge-shaped blocks 11.

Slots 12 are formed in the inner edges 13 of 10 the frame 1 adjacent the corners 14 thereof. Lugs or nail heads 15 are formed on the inner faces of the side walls 16 of the frame 1 in close proximity to the ends thereof.

Formed in the mid-portion of the walls 16 and 15 spaced from the inner face of the walls 4 and 5 are transverse slots 17.

Formed in the mid-portion of the walls 18 and 19 of the frame 1 intermediate the ends of the walls 2 and 3 are cross-like slots 20.

20 The nail heads 15 are adapted to prevent close contact of the wet-plate material 21 with the frame 1 to eliminate damaging the skin thereof.

A plurality of hook-like spring clamps 22 are adapted to hook over the walls 2, 3, 4, and 5 with 25 one end 23 in engagement with the wet-plate 21 whereby to prevent the plate from back sliding. The edges 24 of the wet plate 21 are adapted to engage the inner edges 26 of the wedges 11 which in turn serve to prevent back sliding of 30 the wet plate 21.

The slots 17 and 20 are standard register marks. In Figs. 4 and 5 is shown a modification of the frame 1 wherein the wall 18a is provided with a rectangular slot 18 extending inwardly 35 from the edge 18b thereof. The edges 18c are of dove tail formation as clearly shown in Fig. 5, the inner wall 18d of the slot being provided with an opening 18e. A plurality of register blocks 27 are adapted to be removably mounted in the 40 slots 18, the plate 27a having longitudinal slots 28 arranged in step formation this indication being used in photo-engraving. In Fig. 6 the block 27b is provided with a cross-shaped slot 29, this indication being used for "negative" on exposed 45 material. In Fig. 8 block 27c is provided with a slot 30 whereby to provide a cross-like rib 31 and used as an indication for "positive" on exposed material.

Either or all of the blocks 27 may be used for 50 offset reproduction or for rotogravure reproduction it being unnecessary to change the indications 17.

The slots 12 are used as "negative" corner marks, and "positive" on exposed material. The 55

slots 12 facilitate uniform ruling and opaqueing on exposed plates, eliminating blur of the colored picture.

In Figs. 9 to 12 inclusive is shown a modified 5 form of frame 32, which consists of an L shaped top rail 33 and bottom rail 34. The rails 33 and 34 are provided with a plurality of slots 35 arranged in predetermined position on the horizontal legs 36 and 37 thereof respectively.

10 Upright rails 38 and 39 of L shaped formation are provided with legs 40 and 41 respectively. The legs 40 and 41 are provided with lugs 41a projecting outwardly from the ends thereof: which are adapted to be arranged in certain of 15 the slots 35 for various size plates.

The legs 40 and 37 are provided with wedge shaped lugs 42. The legs 43 and 55 of the rails 38 and 39 respectively are provided with register marks 45 and legs 33 and 34 are provided with 20 register marks 46, and are cut off as at 47 to abut the edges of legs 33 and 34, as clearly shown in Figs. 9 and 10. Nail heads 48 are provided on the legs 43 and 44.

From the foregoing it will be seen that any 25 number of plates may be exposed according to the number of colors desired and all plates will have the same register marks fitting perfectly with each other.

When it is desired to add lettering to direct 30 color photography with the aid of the device, type in white or color can be added to the negative or positive of the finished direct color exposures (screen or continuous tone) by stripping the composed or drawn lettering, either positive 35 or negative, in tints or solid, just as desired.

It is to be understood that various changes in the detail of construction may be made without departing from the spirit of the invention.

Having thus described my invention, what I 40 claim is:

1. A device of the class described, including in combination a rectangular frame, a rectangular rib extending entirely around said frame adjacent the front edge thereof, an inwardly extending relatively narrow front wall on said frame, 45 jaws of saw-tooth formation formed on said rib extending laterally therefrom adjacent the corners thereof, and wedge blocks formed on the inner face of one side and bottom wall of said frame in close proximity to the ends thereof, said blocks having outwardly tapered front ends terminating adjacent said front wall, said front wall having register slots formed intermediate the ends thereof.

50 2. A device of the class described, including in combination a rectangular frame, a rectangular rib extending entirely around said frame adja-

cent the front edge thereof, an inwardly extending relatively narrow front wall on said frame, 5 jaws of saw-tooth formation formed on said rib extending laterally therefrom adjacent the corners thereof, wedge blocks formed on the inner face of one side and bottom wall of said frame in close proximity to the ends thereof, said blocks having outwardly tapered front ends terminating adjacent said front wall, said front wall having 10 rectangular slots extending inwardly from the edges thereof, tapered side walls formed in said slots, and perforated register blocks having tapered sides mounted in said slots.

3. A device of the class described, including in combination, a rectangular frame, a rectangular 15 rib extending entirely around said frame adjacent the front edge thereof, jaws of saw tooth formation formed on said rib extending laterally therefrom adjacent the corners thereof, an inwardly extending relatively narrow front wall on 20 said frame said front wall having rectangular slots extending inwardly from the edges thereof, tapered side walls formed in said slots, and perforated register blocks having tapered sides mounted in said slots.

25 4. A device of the class described, including in combination, a rectangular frame, a rectangular rib extending entirely around said frame adjacent the front edge thereof, jaws of saw tooth formation formed on said rib extending laterally 30 therefrom adjacent the corners thereof, an inwardly extending relatively narrow front wall on said frame said front wall having rectangular slots extending inwardly from the inner edges thereof, tapered side walls formed in said slots, 35 perforated register blocks having tapered sides mounted in said slots, and means for clamping a wet plate to said front wall.

5. A device of the class described, including in combination, a rectangular frame, a rectangular 40 rib extending entirely around said frame adjacent the front edge thereof, an inwardly extending relatively narrow front wall on said frame, 45 jaws of saw-tooth formation formed on said rib extending laterally therefrom adjacent the corners thereof, wedge blocks formed on the inner face of one side and bottom wall of said frame in close proximity to the ends thereof, said blocks having outwardly tapered front ends terminating adjacent said front wall, said front wall having 50 rectangular slots extending inwardly from the inner edges thereof, tapered side walls formed in said slots, and perforated register blocks having tapered sides mounted in said slots, said frame having end walls adjustably mounted in the top 55 and bottom walls thereof.

KARL KLOPP.
